(57) **CLAIM**

An ornamental design for a camera raincoat with opening on the bottom, as shown and illustrated.

DESCRIPTION

FIG. 1 is a perspective view of a camera raincoat with opening on the bottom showing my new design;

FIG. 2 is a front view thereof;

FIG. 3 is a right side view thereof;

FIG. 4 is a top view thereof;

FIG. 5 is a left side view thereof;

FIG. 6 is a bottom view thereof; and,

FIG. 7 is a rear view thereof.

The broken lines shown in the drawings are for environmental structure only and form no part of the claimed design.
